167,732

COLLECTING TRAY

Augusto Alba, San Francisco, Calif.

Application April 14, 1951, Serial No. 14,845

Term of patent 14 years

(CL. D44—10)

To all whom it may concern:

Be it known that I, Augusto Alba, a citizen of the Republic of Argentina, residing at the city and county of San Francisco, State of California, have invented a new, original, and ornamental Design for Collecting Tray, of which the following is a specification, reference being had to the accompanying drawing, forming a part hereof.

Fig. 1 is a perspective view of a collecting tray, showing my new design;

Fig. 2 is a top plan view; and

Fig. 3 is a side elevational view thereof.

I claim:

The ornamental design for a collecting tray, as shown.

AUGUSTO ALBA.
